UNITED STATES PATENT OFFICE.

WESLEY HARPER TRIPPETT, OF REDLANDS, CALIFORNIA.

MAGAZINE-PISTOL.

SPECIFICATION forming part of Letters Patent No. 606,493, dated June 28, 1898.

Application filed January 2, 1897. Serial No. 617,747. (No model.)

To all whom it may concern:

Be it known that I, WESLEY HARPER TRIPPETT, of Redlands, in the county of San Bernardino and State of California, have invented 5 certain new and useful Improvements in Firearms, of which the following is a full, clear, and exact description.

The object of the invention is to provide certain new and useful improvements in firearms—such as revolvers, rifles, and the like—whereby a large number of cartridges can be carried in the magazine and brought singly and successively in proper position for firing.

The invention consists of certain parts and 15 details and combinations of the same, as will be fully described hereinafter and then pointed out in the claims.

Reference is to be had to the accompanying drawings, forming a part of this specification, 20 in which similar characters of reference indicate corresponding parts in all the figures.

Figure 1 is a side elevation of the improvement as applied to a revolver with parts in section. Fig. 2 is a plan view of the same, 25 and Fig. 3 is a perspective view of the inner cylinder-guard.

The firearm shown in Figs. 1 and 2 is provided with a stock or handle A, a barrel B, and a frame C, through which is adapted to 30 pass a ring-shaped magazine D, provided with a bottom plate having a central opening by which it is mounted to turn on a pivot E, carried by the stock, the axis of the magazine standing at an angle to the axis of the barrel 35 B, as plainly indicated in Fig. 1. The magazine D is provided with bores D', adapted to receive the cartridges F, the bores being arranged radially in the ring-shaped magazine and with their axes at angles other than 40 ninety degrees to the axis of the magazine. Now when the magazine is in position on the firearm then it stands in an inclined position relatively to the barrel, and the uppermost bore D' when passing through the frame C is brought into alinement with the bore in the barrel B, and consequently the cartridge contained in this bore can be fired to send a bullet through the barrel.

The usual or any other suitable mechanism 45 for intermittently turning the magazine D to bring the cartridges in alinement successively with the barrel B can be employed, and I do

not limit myself to any special means for revolving the said magazine. An external cup-shaped guard G, fixed to the stock or other 55 part of the firearm, engages the magazine, so as to hold the cartridges contained therein in place, the said guard being formed with an opening G' for the hammer or firing-pin to fire the cartridge. A second opening G² is 60 formed in the guard G at one side of the frame to permit of conveniently filling the magazine with cartridges and to remove the shells from the magazine. The flange of the guard G is formed at the inside with a groove 65 G³, which extends around the flange and serves to protect the caps of the cartridges. The guard G may be made in sections and terminate at the frame or go through it, as shown.

An inner guard H, made cup-shaped, is supported at its bottom on the pivot E, and the flange H' of this guard extends on the inner face of the magazine D. In the flange H' is formed an opening H² for the passage of the 75 bullet from the magazine D to the barrel B when the cartridge is fired. The flange H' decreases in thickness toward the opening H², as plainly shown in Figs. 2 and 3, so that the sharp edges of the flange at the opening bear 80 close upon the magazine to prevent any matter incident to the burning of the powder becoming lodged between the magazine and the guard. Any such matter, owing to the said sharp edges, will readily pass into the cup-shaped guard, to be removed therefrom whenever desired.

It will be seen that by the arrangement described a very large number of bores can be formed in the magazine for carrying a large 90 number of cartridges. Thus the user is enabled to fire a large number of shots before it is necessary to reload.

By using a magazine of this form and placing it in an inclined position relatively to the 95 barrel and stock the thickness of the weapon is greatly diminished at the breech and the weapon can be conveniently carried in one's pocket, with the handle standing at right angles to the pocket to permit of conveniently 100 drawing the weapon whenever desired.

Having thus described my invention, I claim as new and desire to secure by Letters Patent—

1. A firearm provided with a magazine mounted to turn and having a ring-shaped rim formed with bores adapted to contain cartridges, the axis of the said magazine standing at an inclination to the axis of the barrel of the firearm and the rim and bores standing at an inclination to the axis of the magazine, substantially as shown and described. 5
2. A firearm provided with a magazine mounted to turn beneath the barrel, the rim of the magazine being provided with bores the axes of which stand at an inclination to the axis of the magazine, substantially as shown and described. 10
3. A firearm having a pivot located under the barrel of the firearm and standing at an inclination thereto, and a magazine mounted to turn on said pivot and made ring-shaped, the rim of the magazine being inclined to the 15 axis of the magazine and passing through the frame of the firearm, substantially as shown and described.
4. A firearm having a pivot located under the barrel and arranged at an inclination thereto, and a magazine mounted to turn on the said pivot and made ring-shaped, the rim of the magazine being formed with bores inclining downwardly and outwardly with respect to the axis of the magazine, the said 20 rim passing through the frame of the firearm at the rear of the barrel, substantially as set forth. 25
5. A firearm provided with a magazine adapted to contain cartridges, the said magazine being mounted to turn under the barrel, the rim of the said magazine being inclined to the axis of the magazine and provided with bores, whereby when the magazine is turned, the bores are successively brought into alignment with the barrel of the firearm at the rear thereof, and an external guard for the magazine for holding the cartridges in place, substantially as shown and described. 35
6. A firearm provided with a magazine adapted to contain cartridges and mounted to turn under the barrel, the said magazine being ring-shaped and having its rim extending downwardly and outwardly at an inclina- 40
- tion to the axis of the magazine, the said rim being formed with radially-arranged bores 50 adapted to be brought into alignment with the barrel of the firearm, substantially as shown and described.
7. A firearm provided with a transverse opening at the rear of the barrel and in line therewith, a ring-shaped magazine mounted to turn on a pivot located under the barrel and having its rim inclining downwardly and outwardly and provided with bores, the said rim extending through the transverse opening at the rear of the barrel and an external guard for the magazine made cup-shaped and having an opening in its flange to permit of filling the magazine with cartridges, substantially as shown and described. 55
8. A firearm provided with a ring-shaped magazine pivoted beneath the barrel, said magazine having in its rim radially-arranged bores adapted to contain cartridges, said rim and bores inclining to the axis of the magazine and adapted to pass through an opening in the frame of the firearm at the rear of the barrel, and a cup-shaped inner guard for said magazine, the said guard having a flange formed with an opening at its rear for the 60 passage of the bullet from the magazine to the barrel, the flange decreasing in thickness toward said opening, substantially as shown and described. 65
9. A ring-shaped magazine for firearms having its rim provided with radially-arranged bores, the axes of the said bores being inclined to the axis of the magazine, substantially as shown and described. 70
10. A magazine for firearms provided with a bottom plate having a central pivot-opening, and a ring-shaped rim provided with radially-arranged bores, the said rim being connected with the said plate and inclining downwardly and outwardly with respect thereto, substantially as shown and described. 75
